UNITED STATES PATENT OFFICE.

THOMAS S. RAYNER, OF SPRINGFIELD, OHIO, ASSIGNOR OF ONE-HALF TO
CYRUS T. AND CHARLES WARD, OF SAME PLACE.

PRESS FOR MOLDING FIRE-KINDLING SUBSTANCES.

SPECIFICATION forming part of Letters Patent No. 281,923, dated July 24, 1883.

Application filed February 5, 1883. (No model.)

To all whom it may concern:

Be it known that I, THOMAS S. RAYNER, of Springfield, county of Clarke, State of Ohio, have invented a new and useful Improvement 5 in Presses for Molding Fire-Kindling Substances, of which the following is a specification.

My invention relates to that class of machines that are used for the purpose of compressing and giving form to compounded kindling substances.

The object of this invention is principally to simplify the construction of this class of machines, and thereby render their operation more uniform, and at the same time more convenient.

In the accompanying drawings, Figure 1 is a perspective view of a machine embodying my improvements. Fig. 2 is a perspective view of the plunger, represented as detached 20 from the machine and with its bottom side up. Fig. 3 is a perspective view of the mold and its loose bottom. This is also shown as detached from the machine. Fig. 4 is a longitudinal section, representing the compressing 25 lever and plunger in proper position for compressing and giving form to the kindling substance in the aforesaid mold; and Fig. 5 is a similar view, illustrating the machine in a proper position for the removal of the kindling 30 after it has received the desired shape and solidity.

Similar letters indicate corresponding parts in each of the figures.

I have represented the machine as mounted 35 upon a rectangular stand, *a*, that is supported upon legs *b*.

Upon the stand *a*, I erect a frame composed of the uprights *c* and *e* and connecting cross-bar *d*, for the reception of the plunger *f* and 40 mold *g*.

To the part *d* of the aforesaid frame I secure brackets *h*, that are provided with guideways *i*, for the reception of the cross-head *j* of the compression-lever *k*.

45 The table *a* is provided with a rectilinear board to form a yielding bottom, *m*, on which rests the mold, hereinafter described, when the plunger is brought down. This bottom *m* is made yielding by elastic bearing-pieces *p*, so 50 as to compensate for any uneven delivery of the plunger into the mold. To support the

mold and yet permit it to rock, I provide a ball-bearing at its center; but this is not essential, as the elastic bearing-pieces will of themselves provide for the proper yielding of 55 the bearing to compensate for uneven delivery of the plunger into the mold.

The plunger *f* is confined to its desired course of travel by means of a side guide, *q*, and studs *r s*, between which the projections *t u*, that are 60 formed upon said plunger in a manner suitable for that purpose, are free to slide. The mold *g* is supported by the auxiliary yielding bottom *m*, and is held to place by being slid into grooves *v*, formed in the lower portions 65 of the uprights *c* and *e*. This mold is composed of a loose bottom, *x*, transverse and longitudinal side boards, and vertical partitions *z*, connecting the transverse boards, to provide a series of longitudinal chambers, *w*. The 70 plunger *f* is constructed of any suitable material, and is divided into sections *y*, equal in number and corresponding in configuration to the channels *w*, in which they have to work. When the plunger *f* enters the mold *g*, the partitions *z* pass into the gains *a'*, and the knives *b'* divide the kindling material, which is in a semi-fluid state, into cakes of any desired shape, and the punches *c'* make diagonal perforations in the cakes—one perforation to each 75 cake. After the cakes have been shaped and separated from the body of material from which they are formed, a sufficient time is allowed to pass for them to set. Then the compression-lever is run back until its two pins *l* enter the 80 holes *l'*, formed in the uprights *f'* of the plunger, and said plunger is raised by the lever *k* until the projections *u t* on said plunger are at a suitable position to pass between the studs *r s* on the framing. Then the plunger is moved 85 over bodily until its projections rest upon the projections on the framing. The mold *g* may now be drawn out to the front of the stand, as shown in Fig. 5, and the cakes can be removed by lifting up the mold, which will leave the 90 cakes upon the loose bottom *x*.

It will be observed that the compression-lever *k* is capable of adjustment in the slides *i*. This enables the operator to lift the plunger without raising the lever very much, and also 95 permits of an increased leverage when it is used in compressing the cakes into the mold.

I am aware that presses have been provided with molds having a sliding bottom combined with vertically-movable plungers for forcing the molded blocks from the mold when the bottom of the latter is moved away; and I am also aware that a gang of cutters has been secured to a frame connected with a pivoted lever, by which the frame is raised and lowered to cut and press material into cubes; but such features are not broadly claimed by me.

Having thus described my invention, what I claim as new, and desire to secure by Letters Patent, is—

1. In a machine for compressing and molding plastic kindling material, the combination of a frame-work having studs, a vertically-movable plunger, *f*, having projections at its ends, and means for engaging and raising the plunger to permit it to be moved laterally, to cause its projections to engage the studs on the frame-work and be thereby suspended, substantially as described.

2. The combination of the stand, the frame-work thereon, provided with studs, the plunger arranged to rise and fall within the frame-work and having projections at its ends, the brackets carried by the frame-work, and the swinging lever for raising the plunger and permitting it to be adjusted laterally, to cause its projections

to engage the lugs on the frame-work and be thereby suspended, substantially as described.

3. The combination of the frame-work having brackets *h*, provided with guides *i*, cross-head *j*, having its ends arranged in guides, the lever *k*, connected with the cross-head and provided with pins *l*, and the vertically-movable plunger *f*, having holes *l'*, substantially as described.

4. The combination of the frame-work and stand, the auxiliary bottom *m*, supported on the stand by yielding devices, the removable mold *g*, the vertically-movable plunger *f*, and the lever *k*, having pins *l*, for lifting the plunger, substantially as described.

5. In a machine for molding and compressing kindling material, a plunger, *f*, subdivided into a series of plungers, so as to leave gains *a'*, and having knives *b'* and punches *c'*, in combination with a mold, *g*, having partitions *z* and loose bottom *x*, substantially as and for the purpose described.

In testimony whereof I have hereunto set my hand this 1st day of February, 1883.

THOMAS S. RAYNER.
